GAS LIGHTER

Joaquina Prendes, New York, N. Y.

Application February 26, 1937, Serial No. 127,881

3 Claims. (Cl. 200—34)

This invention relates to new and useful improvements in a gas lighter.

The invention has for an object the construction of a gas lighter which is characterized by a body comprising a base plate and a cover, and an insulation block mounted within the body and having a socket member supporting a plug which extends out from the cover so as to be readily removable.

10 The invention proposes mounting a resistance within the plug and arranging suitable electrical connections on the base plate to provide a circuit which includes the resistance. Furthermore, it is contemplated to connect the negative of a 15 household power circuit to the circuit just mentioned and to continue this circuit to an ignition element.

It is proposed to construct the ignition element of a conductor with a handle of insulated 20 material, so that it may be handled. Then when the conductor is touched to a gas range or other similar contrivance it is possible to produce sparks to ignite the gas.

Another one of the objects of this invention is 25 to arrange the socket in the insulation block in a manner so that it is movable and permits the plug to be depressed. An arrangement is then proposed to force the plug back to its initial position after a pre-determined interval 30 of time and to use this construction to automatically break a circuit through the gas lighter, a short interval of time after the plug is depressed. This is a safeguard to prevent accidental shocking of people.

35 For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of a gas lighter constructed 45 according to this invention.

Fig. 2 is a vertical sectional view taken on the line 2—2 of Fig. 1.

Fig. 3 is a fragmentary enlarged sectional view taken on the line 3—3 of Fig. 2.

50 Fig. 4 is a sectional view of the plug shown in Fig. 3 removed.

Fig. 5 is a fragmentary view similar to Fig. 3 but illustrating a modification of the invention.

55 Fig. 6 is a horizontal sectional view taken on the line 6—6 of Fig. 5.

Fig. 7 is a perspective view showing another modified form of the invention.

Fig. 8 is a vertical sectional view taken on the line 8—8 of Fig. 7.

Fig. 9 is a transverse sectional view taken on the line 9—9 of Fig. 8.

The gas lighter includes a body 10 consisting of a base plate 10^a and a cover 10^b. An insulation block 11 is mounted within the body and particularly on the base plate 10^a. This insulation block has a socket member 12 which includes an end contact 12^a and a shell contact 12^b. A plug 13 is adapted to threaded engage the shell contact 12^b and extends out through an opening 10^c formed in the front wall of the cover 10^b. The plug 13 has a shell contact 13^b and an end contact 13^a engageable respectively with the shell and end contacts of the socket member in the insulation block. A conductor ignition element 15 has a handle 16 of insulation material and is connected in a circuit with a conventional plug 17 adapted to be plugged into the plug of a household electric circuit.

The plug 17 has a positive contact 17^a and a negative contact 17^b. The lead 17^{aa} from the positive contact is taped up by a strip of tape 18 engaged around the insulation cover of a cable 19 which houses the leads. The negative lead 17^{bb} is connected with a terminal 20 mounted on the insulation block 11. This terminal connects with a lead 21 which connects with the end contact 12^a.

The plug 13 has a central opening in which there is a resistance coil 23. This resistance coil connects with an end contact 24 in intimate contact with the end contact 13^a. The other end 35 23^a of the resistance coil connects with the shell contact 13^b. A cap 25 is mounted across the top of the plug 13 and clamps down a mica disc 26 through which the end of the coil 23 may be 40 seen.

The shell contact 12^b is connected with a lead 27 which connects with a terminal 28 mounted on the insulation block 11. This terminal 28 connects with the negative lead 29 of a cable 30. 45 The positive lead 31 of this cable is taped down at its ends by strips of tape 32 and 33 so that it is inoperative. The negative lead 29 at the point 29' within the free end of the handle 50 16 connects with the ignition element 15.

The ignition block 11 has a flat bottom portion 11^a, a central cylindrical portion 11^b, and end channel portions 11^c. Within the end channel portions 11^c the terminals 20 and 28 respectively 55

are mounted. The contact shell 12^b is cemented to the cylindrical portion 11^b.

In Figs. 5 and 6 a modification of the invention has been disclosed which distinguishes from the previous form in the fact that the plug 13' is depressible and controls contact between the end contact 13^a of the plug and the end contact 12^a of the socket. More specifically, the plug 13' has a contact shell 13^b which is screwed into the socket shell 12^{bb}. The socket shell is made from two sections. There is the section 12^{bb} which is movable, and the stationary section 12' which is cemented into the cylindrical portion 11^b of the insulation block.

The stationary section 12' connects with an annular channel shaped member 35 in which an annular member 36 slidably engages. This annular member 36 is fixed to the lower edge of the section 12^{bb}. Diaphragm elements 37 and 38 are connected with the sides of the member 36 and with the sides of the channel 35 and serve to hermetically encase the member 36 within the channel 35.

Several springs 39 are mounted within the annular channel member 35 and act against the bottom edge of the annular member 36 to normally urge it upwards. A vent 40 connects with the area within the channel 35 and beneath the member 36. This vent 40 is controlled by a flexible valve element 41 which normally extends over and covers it. The arrangement is such that when the member 36 is pressed downwards the flexible valve element 41 opens to allow discharge of air. But when the member 36 is released the valve element 41 closes and the member 46 can rise only as the air from the atmosphere seeps into the area beneath the member 36 and within the channel 35.

The terminal 20 is connected by a lead 21 to the end contact 12^a. This lead 21 has a flexible end portion 21' which normally holds the end contact 12^a slightly raised. It may be depressed when the plug 13' is depressed and will follow up the raising action of the plug for a certain distance. In other respects this form of the invention is identical to the previous form and similar parts may be recognized by the identical reference numerals.

The operation of the device is as follows:

With respect to the form of the invention shown in Figs. 1 to 4 there is a continuous circuit from the negative terminal of the plug 17 to the ignition element 15. This circuit passes through the resistance coil 23. To use the lighter it is merely necessary that the ignition element 15 be touched against the gas range burner and sparks which will thus be produced will ignite the gas. When the lighter 15 is not used it is stored upon a hook 45 which is mounted on the side of the body 10 of the gas lighter.

In the form of the invention shown in Figs. 5 and 6 it is necessary that the plug 13' be first pressed down before the ignition element 15 may operate. When the plug 13' is depressed the end contacts 12^a and 13^a will touch each other. The circuit is now closed and will remain closed until the plug 13' moves back to its raised position. The springs 39 will so move the plug. It is necessary that air seep in through the vent 40 to permit the springs 39 to function.

In Figs. 7, 8 and 9 another modification of the invention has been disclosed in which the plug 53' may be pulled out of the body 50 which consists of a base plate 50^a and a cover 50^b. The cover 50^b is secured to a base plate 50^a by prongs 50^{bb}

and is formed with a top opening 50^c. A cover plate 50^e fits over this opening and is provided with a handle 50^d. A pair of supporting rods 50' of insulation material, are secured on the inner face of cover plate 50^e and their free ends are engaged in between forked ends of and secured to the forward free ends 53 of resistance coil 53'.

A pair of spring clips 21' and 27' are secured to insulation block 51 which is mounted on base plate 50^a. The free ends of these clips are adapted to resiliently hold the resistance coil 53'.

The lead 19^b of cable 19 is connected to terminal 20' on one of the clips 21' and the other lead 19^a of cable 19 is connected to an insulated screw 52 on the base plate 50^a. The other clip 27' is provided with terminal 28'. The lead 29 of cable 30 connects to terminal 28' and the other lead 30^a of cable 30 connects to insulated screw 54.

This arrangement permits the removal of resistance coil 53' by cover handle 50^d through 50^e of the cover. In other respects this form of the invention is similar to the previous form, and the various similar parts may be recognized by similar indicating numerals.

In other respects this form of the invention is similar to the preferred forms and identical parts may be recognized by the same reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a device of the class described, a plug, a contact below said plug, a stationary socket section having an annular channel on the bottom thereof, a movable socket section for supporting said plug coaxially within said stationary socket section, an annular member slidably mounted within said channel and fixedly attached to the bottom of said movable socket section and being movable towards said contact, a contact member on said plug and movable with said plug to engage said contact when said annular member is moved in towards said contact, a resilient means urging said annular member into an extended position, diaphragm elements having one of their edges attached to said annular member and the other of their edges attached to the sides of said channel for hermetically encasing the annular member within said channel, a vent and a valve for permitting the air to easily escape from said channel when said annular member is being moved toward said contact and for limiting the entrance of air to said channel when said resilient means is urging said annular member back to its normal position to retard the return movement, and said annular channel being positioned around said plug and between said contact and the top of said plug.

2. In a device of the class described, a plug, a contact below said plug, a stationary socket section having an annular channel on the bottom thereof, a movable socket section for supporting said plug coaxially within said stationary socket section, an annular member slidably mounted within said channel and fixedly attached to the bottom of said movable socket section and being movable towards said contact, a contact member on said plug and movable with said plug to engage

- 5 said contact when said annular member is moved in towards said contact, a resilient means urging said annular member into an extended position, diaphragm elements having one of their edges attached to said annular member and the other of their edges attached to the sides of said channel for hermetically encasing the annular member within said channel, a vent and a valve for permitting the air to easily escape from said channel when said annular member is being moved toward said contact and for limiting the entrance of air to said channel when said resilient means is urging said annular member back to its normal position to retard the return movement, and said 10 10 15 15 20 20 25 25
- annular channel being positioned around said plug and between said contact and the top of said plug, said resilient means, comprising springs operating between the bottom of said annular member and the base wall of said channel.
3. In a device of the class described, a plug, a contact below said plug, a stationary socket section having an annular channel on the bottom thereof, a movable socket section for supporting said plug coaxially within said stationary socket section, an annular member slidably mounted within said channel and fixedly attached to the bottom of said movable socket section and being movable towards said contact, a contact member on said plug and movable with said plug to engage said contact when said annular member is moved in towards said contact, a resilient means urging said annular member into an extended position, diaphragm elements having one of their edges attached to said annular member and the other of their edges attached to the sides of said channel for hermetically encasing the annular member within said channel, a vent and a valve for permitting the air to easily escape from said channel when said annular member is being moved toward said contact and for limiting the entrance of air to said channel when said resilient means is urging said annular member back to its normal position to retard the return movement, and said annular channel being positioned around said plug and between said contact and the top of said plug, said valve, comprising a short piece of flexible material extendable across said vent when said annular member is returning to its normal position.

JOAQUINA PRENDES. 25
